(57) **CLAIM**

The ornamental design for a garlic press, as shown and described.

DESCRIPTION

2.1 is an upper rear perspective view of a garlic press, showing my new design in a closed state;

2.2 is a top view thereof;

2.3 is a bottom view thereof;

2.4 is a right side view thereof;

2.5 is a left side view thereof;

2.6 is a front elevation view thereof;

2.7 is a rear elevation view thereof;

2.8 is an upper rear perspective view in an open state;

2.9 is an upper rear perspective view of a first component of the garlic press;

2.10 is a lower rear perspective view thereof;

2.11 is a top view thereof;

2.12 is an upper rear perspective view of a second component of the garlic press;

2.13 is a top view thereof;

2.14 is a right side view thereof;

2.15 is a left side view thereof;

2.16 is a front elevation view thereof; and

2.17 is a rear elevation view thereof.

The dash-dash broken lines showing portions of the article form no part of the claimed design; the dash-dot broken lines showing a boundary form no part of the claimed design; views Nos. **2.1-2.7**: closed state; view No. **2.8**: open state; views Nos. **2.9-2.11**: explanatory views of the first component part; views Nos. **2.12-2.17**: explanatory views of the second component part.
